UNITED STATES PATENT OFFICE.

FELIX KIELLINSKI, OF MILWAUKEE, WISCONSIN.

TROLLEY.

1,257,245.

Specification of Letters Patent. Patented Feb. 19, 1918.

Application filed April 19, 1917. Serial No. 163,250.

To all whom it may concern:

Be it known that I, FELIX KIELLINSKI, a citizen of the United States, residing at Milwaukee, in the county of Milwaukee and State of Wisconsin, have invented certain new and useful Improvements in Trolleys, of which the following is a specification.

This invention relates to trolley poles and harps.

10 One important object of the invention is to provide an improved form of trolley pole and harp wherein the harp may have an improved swivel connection to the pole.

15 A second important object of the invention is to provide an improved device of this character which will swivel automatically as a car goes around a curve so that the line of pressure which is the resultant of a vertical component due to the action of 20 the usual spring on the trolley pole and a horizontal component due to centrifugal action, will pass through the wire and thus the tendency of the trolley wheel to jump off of the wire will be practically eliminated.

25 With the above and other objects in view, such as will be hereinafter apparent the invention consists in general of certain novel details of construction and combinations of 30 parts hereinafter fully described, illustrated in the accompanying drawing, and specifically claimed.

35 In the accompanying drawing, like characters of reference indicate like parts in the several views, and:—

Figure 1 is a side elevation of the upper end of a trolley pole and harp showing the improved construction.

Fig. 2 is a plan view thereof.

40 Fig. 3 is a section on the line 3—3 of Fig. 1.

Fig. 4 is a median section on the line 4—4 of Fig. 1.

45 Fig. 5 is a detail section on the line 5—5 of Fig. 4.

Fig. 6 is a perspective view of a pivot pin used herewith.

Fig. 7 is a vertical section on the line 7—7 of Fig. 4.

50 Fig. 8 is a plan view of a portion of a car showing the position assumed by the wheel in passing around a curve, the view being somewhat conventionalized to avoid confusion in the details.

55 Fig. 9 is a detail view of a spring clamp used herewith.

Fig. 10 is a detail view of a modified arrangement of spring centering device, the view being taken on the same line as Fig. 7.

In the embodiment of the invention herein 60 illustrated there is shown a trolley pole 10 having a head 11 screwed on the upper end thereof. Screwed into the top of this head 11 is the lower threaded portion 12 of a pivot pin having a central polygonal portion 13 65 and an upper cylindrical portion 14. Seated on the top of the head 11 is a washer 15 having a polygonal opening to receive the polygonal portion 13 of the pivot pin and in the upper face of this washer is a ball race 70 16 concentric to the pivot pin. Revoluble on the cylindrical portion 14 of the pivot pin is an upper washer 17 likewise having a ball race 18 which confronts the ball race 16. Held between these ball races are the bearing 75 balls 19 by means of which the upper plate 17 may freely and easily revolve on the pivot pin. Fixed to the upper washer 17 is a U-shaped harp 20 wherein is revolubly supported a trolley wheel 21, the upper plate 80 and harp being held on the pin 14 by a key 22. Projecting upward from the plate 15 is a pin 23 which passes through an arcuate slot 24 formed in the upper washer 17 and on each side of the pin is a coil spring 25, 85 these springs normally holding the pin centrally of the arcuate slot. Thus while the balls permit a free and steady movement of the harp on the axis of the pole yet the springs always act to restore the wheel to its 90 normal position, while the ends of the slot 24 prevent too great movement of the trolley wheel on the axis of the pole.

Now, under ordinary circumstances, as when traveling under a straight track, the 95 trolley wheel will be maintained in its usual position. When the car, however, goes around a curve the harp will assume the position shown in Fig. 8 so that the wire 26 100 will lie off to the outer side of the curve, the trolley pole rising slightly and the coil springs permitting an angular disposition of the wheel with reference to a vertical plane through the axis of the pole. The tendency of the free end of the pole is, of 105 course, to swing toward the outer side of the curve and also to rise. The rising movement is resisted by the limiting action of the pin and slot while the tendency to swing outward is resisted by the pressure of the 110 wire on the wheel so that the wire is always kept in the bottom of the groove of the

trolley wheel and thus the wheel is prevented from jumping off the wire.

In addition to the springs 25 I preferably employ a hook-shaped spring clamp 26 which is fixed to the lower washer 15 and is provided with a head 27 riding on the upper surface of the upper washer so as to hold the upper washer frictionally against movement.

10 In place of the springs 25 and pin 23 I may also employ a coil spring 28 one end of which is fixed to the polygonal portion 13 of the center pin while the other end is connected to the upper washer 17, the spring lying in a recess 29 in the upper washer. I may also employ both this spring 28 and the springs 25 if I see fit.

It is obvious that many minor changes may be made in the form and construction 20 of the invention without departing from the material principles thereof. It is not therefore desired to confine the invention to the exact form herein shown and described but it is wished to include all such as properly come within the scope claimed.

Having thus described the invention, what is claimed as new, is:-

1. The combination with a trolley pole; of a head screwed on the upper end of said 30 pole, a pivot pin having a polygonal central portion and having one end threaded and screwed into the top of said head, the remaining end being smoothly cylindrical, a washer fitted on the polygonal portion of the

pin and resting on top of the head, said 35 washer having a ball race concentric to the pin in its upper face, a second washer revolvably mounted on the cylindrical portion of the pin and having a ball race on its lower surface confronting the first-mentioned ball 40 race, balls resting in said races, a U-shaped harp fixed to the upper surface of the upper washer, and a trolley wheel carried by said harp.

2. The combination with a trolley pole; 45 of a head screwed on the upper end of said pole, a pivot pin having a polygonal central portion and having one end threaded and screwed into the top of said head, the remaining end being smoothly cylindrical, a 50 washer fitted on the polygonal portion of the pin and resting on top of the head, said washer having a ball race concentric to the pin in its upper face, a second washer revolvably mounted on the cylindrical portion of 55 the pin and having a ball race on its lower surface confronting the first-mentioned ball race, balls resting in said races, a U-shaped harp fixed to the upper surface of the upper washer, and a trolley wheel carried by said 60 harp, resilient means normally holding the upper washer against movement relative to the lower washer.

In testimony whereof I affix my signature.
FELIX KIETLINSKI.
